US00D778280S

(12) **United States Design Patent** (10) Patent No.: **US D778,280 S**
 Vanderpol et al. (45) Date of Patent: ** Feb. 7, 2017

(54) **STORAGE DRIVE**(71) Applicant: **Western Digital Technologies, Inc.**,
Irvine, CA (US)(72) Inventors: **Gregory A. Vanderpol**, Long Beach,
CA (US); **Steven Tzu-Yen Peng**, Irvine,
CA (US)(73) Assignee: **Western Digital Technologies, Inc.**,
Irvine, CA (US)(**) Term: **14 Years**(21) Appl. No.: **29/522,307**(22) Filed: **Mar. 30, 2015**
